UNITED STATES PATENT OFFICE.

CHARLES W. EBERHARD, OF PALATINE, ILLINOIS.

MATRIX AND METHOD OF MAKING SAME.

Application filed January 16, 1924. Serial No. 686,616.

To all whom it may concern:

Be it known that I, CHARLES W. EBERHARD, a citizen of the United States of America, and a resident of Palatine, county of Cook, and State of Illinois, have invented a new and useful Improvement in Matrices and Methods of Making Same, of which the following is a specification.

This invention relates to stereotype, and especially to the make-up and structure of matrices and to methods of forming same ready to be used in a mold for casting stereotype plates.

The main objects of the invention are to provide an improved form of matrix, adapted to hold its original and desired form effectually when used in a stereotype casting box; to provide distributed backing means for the matrices, substantially integral therewith, sufficient to prevent deformation or bulging of the matrix wall or any part thereof incident to casting stereotypes; to provide matrices embodying this invention adapted for immediate use in stereotype molds without the application of make-ready shims or adjusting strips on the back; to provide distributed non-yielding means on the backs of the matrices, prior to removal from the type forms, adapted to provide substantially a uniform planar bearing for the back of the matrix when it is put in a stereotype mold; to obviate the need of manual application and adjustment of make-ready means either to the stereotype plate or to the matrix; to provide a convenient and effective method of producing and applying the distributed backing filler part to the main body of the matrix; to provide for accomplishing the desired planar back finish automatically in the process of making and finishing the matrix and to provide for accomplishing these ends without need of altering any of the usual machines and implements used in making matrices and stereotype plates.

An illustrative embodiment of this invention is shown by the accompanying drawings, in which—

Figure 1 is a face view of a corner of one of the matrix filler backing sheets showing indented upstanding projections.

Fig. 2 is a similar view greatly enlarged.

Fig. 3 is a section on the line 3—3 of Fig. 2.

Fig. 4 is a section showing a pair of

roughening die plates with an unformed moist backing sheet disposed there-between ready for formation by mutual convergence and interfitting of said die plates.

Fig. 5 is a face view of a flong sheet before application to the type form.

Fig. 6 is a section on the line 6—6 of Fig. 5 after pressure application of the flong to the type form whereby it assumes the character of a matrix.

Fig. 7 is a section through a finished matrix having a backing sheet attached adhesively thereto, the section being taken substantially as in Fig. 6.

Fig. 8 is a greatly enlarged view, otherwise similar to Fig. 7, the supporting character of the partially squashed and accurately fitting backing member being prominently featured.

Fig. 9 is a magnified fragmentary section 75 through one of the upstanding roughening projections of a backing sheet before use.

Fig. 10 shows the nature of deformation which occurs when one of these projections is crushed and partly restored to its original 80 flush position, in steam press application of the make-ready sheet to the matrix.

Fig. 11 shows a similar fragmentary view with the projection further crushed and restored, substantially to its original flush 85 position.

Fig. 12 shows, in vertical cross-section, a stereotype casting box or mold with the matrix in place and with a cast stereotype plate ready for removal.

Fig. 13 shows on an enlarged scale the relative position and form of the die plates and backing sheet when the latter is gripped by the die members.

Fig. 14 shows on a reduced scale how the 95 backing sheet mold members (of Fig. 4) may be made in the form of rolls instead of plates.

Fig. 15 shows how the backing sheet may be applied with its flat side pasted to the 100 flong member.

Fig. 16 shows a good form of projection somewhat disk shaped.

Referring to the drawings, the finished matrix 1 of unitary character comprises a 105 flong part 2 and a backing part 3 adhesively secured together substantially integrally. The flong part 2 is of nearly uniform thickness and density, but has slight variations due to thickness variations in the component 110

layers of material, as usual for matrices. The part 3 though not solid throughout is substantially rigid and furnishes a firm and substantially planar back for the matrix.

- 5 It is of variable thickness according to the contour of the back surface of the flong member and its density as a whole varies inversely as the thickness, as will be apparent, due to the voids scattered over and 10 throughout its body. It serves as a space filler and leveling device for the matrix.

When the finished matrix is placed in the casting box one end bears against the box part 4, and the supporting part 3 of the 15 matrix bears against the box wall 4'. The molten metal is poured into the space between the matrix 1 and the box wall 4" to form the stereotype plate 5. The part 3 supports the back of part 2 throughout 20 and prevents any deformation thereof.

In making matrices the back member 3 is initially in the form of a flat smooth sheet 3' as shown in Fig. 4. This sheet is composed of material which when dry 25 is normally hard and effectually resistant to such compression or flattening forces as it may ordinarily be subjected to in casting stereotypes and in handling. But when moist the sheet 3' yields readily to pressure and molding without tearing or breaking. Such sheets are first moistened and then initially molded, as shown by Figs. 30 4, 13 and 14 into the form shown by Figs. 2, 3 and 9, with numerous hollow disks or 35 cup-like projections 6 of dome-shaped hollow character. In molding the domes 6 the material may be stretched and thinned somewhat, or it may even tear a little, but this is negligible and immaterial. The shape 40 of these domes may be varied somewhat, as at 6^a on sheet 3^a of Fig. 16.

Referring to Fig. 4, the complementary die plates 7 and 8 are formed with numerous hollows 9 and projections 10 respectively in mutual registry, the hollows being 45 sufficiently larger than the projections to accommodate the thickness of sheet 3', when the latter is being molded, as in Fig. 13, between said plates, into the form shown 50 by Figs. 2 and 3. The sheet 3' is of the nature of paper, but its composition may be varied widely, though a fibrous material is preferred. It is about 25/1000 of an inch thick. The domes 6 are about 55 75/1000 of an inch high and about 3/16 of an inch apart on centers, though these dimensions may vary according to service requirements.

The paper or other material, as for instance, ordinary matrix paper, for the sheet 60 3' is first treated with a gum or the like, preferably a gummy paste, and a filler of earthy character to give it strength. Certain pigment earths are well adapted for 65 this purpose, the need being to render the

sheet hard and resistant when dried, though soft and yielding when moist. When such a sheet is applied to the back side of a matrix part 2, with a little paste or other adhesive material to make it stick permanently, and light pressure is applied, it readily conforms to the shape thereof. It holds its molded shape effectually and serves as a firm straight-back support for the face 70 part 2 of the matrix. The outer face is 75 substantially planar and fits against the mold wall 4'. Either the rough side 11 or the smooth side 12 may be applied next to the flong part, and the part 3 may be very slightly moist, but I prefer to use it 80 dry.

The backing filler sheet 3 compensates also for any variations in the thickness of the flong body, incident to the usual inherent qualities of even the best grades of paper, all of which vary somewhat in thickness throughout their whole area. Hence, as viewed in Figs. 8 and 15, the type face plane 13 of the matrix is uniformly parallel with the planar back face of the variably compressed filler 3, and the intertype parts 14 of the part 2 are supported by the protuberances 6 which may be more or less squashed and flattened, with variable shaped voids 15 interspersed. Pasting is facilitated by applying face 12 to the flong, as in Fig. 15, but the roughened face 11 adapts itself most readily to the uneven flong back and a smooth face is presented to the casting box wall 4' when the rough side 11 95 is inward, as in Fig. 7.

Although the method of forming the matrix filler-backing sheets 3 is illustrated by flat mold plates 8 and 9 (Fig. 4) it should be understood that the members 8 and 9 may 100 be modified, as in Fig. 14, to take the form of rolls 8' and 9' adapted to handle a continuous strip 3" of backing material, and that stock may be cut from rolls of such 105 backing as required.

According to my preferred method of practicing this invention, a moist flong 2 is applied to the type form (not shown) and together they are run through a roller press (also not shown), or otherwise subjected to 110 molding pressure, whereby the main body or face part of the matrix is formed, after which the matrix member is dried or baked, while in place on the type form, in a screw 115 press substantially as usual in the matrix forming art, though not here shown. The next step involves the present invention, and consists in applying an indented filler support member or backing sheet 3 (see Fig. 1) 120 of impressionable character to the now uneven back of the dried matrix, the latter still resting on the type form. Before bringing these two components together adhesive material is applied preferably to the backing 125 3, so as to cause them to adhere per- 130

manently. Either side of the backing 3 may be presented to the member 2. The matrix with the backing sheet 3 in place, together with the type form, is again placed in a 5 heated screw press where a light pressure is briefly applied, sufficient to mold the backing sheet into snug-fitting relation to the matrix, and also harden same, with the back perfectly plain to correspond with the face 10 of the press plate 4'. The matrix with the backing sheet now securely adherent thereto is removed from the type form and is ready for the stereotype casting box where it is immediately set in place and the desired 15 plates cast. From this stage of the process the several steps in preparing the printing plates are in accordance with the usual practice, except that the perfectly formed and unyielding matrix insures perfect printing 20 plates requiring none of the usual manual adjustment and fitting of the plates ready for the press.

By my invention I make a perfect matrix, and thus obviate the usual need of applying 25 make-ready means to the stereotype plates, which plates being accurately cast fit perfectly in the press without leveling adjustments, as will be understood by all stereotypists. Furthermore, I depend on the use 30 of standard well-known materials and simple methods, such as are readily understood by papier-mâché workers and nearly all who have to do with stereotyping. The essential steps are confined practically to 35 simple molding and drying operations. None of the materials have to become solvent in any stage of the molding process. No intricate or expensive equipment is required.

Although but one complete specific embodiment of this invention is herein shown and described, it is to be understood that numerous details of the method and product described and shown may be altered or omitted without departing from the spirit 45 of the invention as defined by the following claims.

I claim:

1. A stereotype matrix having a fibrous 50 backing filler member substantially integral therewith and providing a normally non-yielding bearing to support the matrix as a whole against yielding in casting stereotypes, which member is formed to provide

distributed positive supports for the inter-type portions of the matrix. 55

2. A stereotype matrix comprising in unitary combination a type molded flong member and back leveling sheet member coextensive with said flong member and having spacer projections struck up more or less 60 thereon according to the back contour of the flong member to hold the main body of the leveling member in a planar position parallel with the type face plane. 65

3. A stereotype matrix backing member in the form of sheet material having dome shaped spacers struck up thereon, which spacers are normally resistant but moldably yielding under heavy pressure. 70

4. The method of making a stereotype matrix which consists in applying to the back of a flong member, after it has been formed on its face side into matrix shape, a yielding backing sheet, and then pressing the latter tightly against the back of the 75 flong member and at the same time thereby forming an effective outer bearing surface of planar character to fit the bed of the stereotype mold. 80

5. The method of making a stereotype matrix which consists in molding a flong 85 into matrix shape and then permanently affixing to the back thereof in a substantially integral manner a back filler supporting member having a substantially uniformly effective outside bearing face and sufficient body to properly support all parts of the flong member when the matrix is in the stereotype mold box and metal is poured 90 into the latter. 90

6. The method of making a matrix which consists in molding a flong to type form, also molding a hard setting backing filler into a form having projections and hollows, applying paste to one of said members bringing 95 said members together with the back of the flong member next to the filler, subjecting them to pressure under heat sufficient to cause the filler to yield and conform to the contour of the adjacent side of the flong 100 whereby the back bearing face of the matrix is rendered true and parallel with the face plane of the type. 100

Signed at Chicago, this 4th day of January, 1924.

CHARLES W. EBERHARD.
